UNITED STATES PATENT OFFICE

2,486,511

APPARATUS FOR RECEIVING FACSIMILE SIGNALS

Charles J. Young, Princeton, N. J., assignor to
Radio Corporation of America, a corporation
of Delaware

Application October 31, 1945, Serial No. 625,891

9 Claims. (Cl. 178—11)

1

The present invention relates to apparatus for receiving facsimile signals and more particularly, although not necessarily exclusively, to a novel arrangement for producing a record in accordance with frequency modulated image signals.

The principal object of the present invention is to provide recording apparatus for producing marks which will operate directly under the control of a frequency modulated signal, thereby obviating the need for the usual printer amplifier, or the need for a discriminator or the like for deriving amplitude modulated signals from the frequency modulated signals.

In accordance with the invention, a frequency modulated carrier signal is applied directly to a recording unit which responds to the marking and/or spacing signals of a given frequency. This result is accomplished without recourse to the phenomena of mechanical resonance so that marks produced in accordance with the invention are free or substantially free of a dot pattern.

Accordingly, another important object of the invention is to provide a recording unit capable of assuming a continuous operating condition so as to exert substantially continuous recording pressure without recurring percussive effects when excited with alternating current of carrier frequency.

A further object of the invention is to provide a novel tape recorder which is responsive to signals of varying frequency.

Other objects and advantages of the present invention will, of course, become apparent and immediately suggest themselves to those skilled in the art to which the invention is directed from a reading of the following specification in connection with the accompanying drawings in which:

Fig. 1 is a diagrammatic showing of a transmitting station for providing signals which are frequency modulated in accordance with the scanning of a piece of subject matter;

Fig. 2 shows, illustratively, recording apparatus embodying the invention;

Fig. 3 shows a desired relationship of filter response curves in accordance with the invention;

Fig. 4 is a detail of the apparatus of Fig. 2;

Fig. 5 is a diagrammatic showing of a slight modification of the recording arrangement of Fig. 2; and

Fig. 6 shows a further modification of the receiving apparatus of the invention.

Referring to the drawings and more particularly to Figs. 1 and 2 thereof, a facsimile system is shown by way of example for transmitting and

2

receiving signals derived as a result of scanning pictures, drawings, or other subject matter. The signals so derived and a carrier modulated with these signals will be referred to as "image signals" for the sake of brevity. The invention is concerned more particularly with a modulating system in which a characteristic of a carrier wave other than the amplitude, for example the frequency, is varied.

10 In Fig. 1 the subject copy is shown as being in the form of a tape 12 bearing printed characters, or the like 14, which are to be scanned for the purpose of producing image signals for transmission to a more or less remote point for intelligence communication purposes. The tape 12 is guided on suitable rollers 15 and 16, one of which, roller 16, for example, may be power driven as shown through the medium of a motor 18 and a gear box 21 or the like containing suitable mechanism to correlate the movement of the tape 12 with the rotation of a scanning element 22. The motor 18 may be of the alternating current synchronous type connected to an alternating current service connection 19. A light source such as an incandescent lamp 23 provides a spot of light on the tape which excites a photocell 24. A tape scanner generally of this type is shown in the United States Patent No. 2,222,937, granted to G. L. Dimmick on November 26, 1940. Other means for producing image signals as a result of scanning may of course be employed.

15 The image signals from the photocell 24 are amplified in an amplifier 26 and are employed to vary the frequency of a carrier wave in a modulator indicated at 27. The output of the modulator is used in turn to modulate radio waves produced and radiated from a radio transmitter 29. A suitable system having equipment such as that shown in Fig. 1 is disclosed in greater detail in the United States Patent No. 2,326,740, granted to Maurice Artzt on August 17, 1943.

20 A receiving station is shown in Fig. 2 of the drawings which includes a disclosure of recording apparatus embodying the invention in one form. A radio receiver 33, which includes a detector for recovering the intelligence bearing signal, such as is produced by the modulator 27 of Fig. 1, furnishes the recovered signal to an amplifier 34. It will be understood that the amplifier 34 may be included in the radio receiver 33 in the form of an audio amplifier normally employed to operate a loudspeaker.

25 By way of example, the transmitting system so far described and the receiver 33 provide signals in the output of the amplifier 34 the frequency

of which varies in accordance with the light and dark areas on the subject copy, such as the tape 12, at the transmitter. The modulator 27 of the transmitter may provide two signalling frequencies, for example, one of which appears when a dark portion of the subject copy is scanned and the other of which appears when a light portion of the subject copy is scanned. It will be assumed for purposes of illustration that when a dark portion of the subject copy 12, such as a letter or a character 14 appearing thereon, is scanned, a frequency in the neighborhood of 1650 cycles will be reproduced, and when the background is scanned, which in this instance is the unmarked tape, a frequency in the neighborhood of 1150 cycles will be produced. These frequencies will appear in the output of the radio receiver 33 to be amplified in the amplifier 34. It will be understood that the frequency values are selected solely for the purpose of explaining the illustrative embodiment of the invention and that other frequencies may be generated and/or transmitted. The order of the frequencies may, of course, be reversed.

In the illustrative recorder of Fig. 2, a record blank, such as a recording tape 38, receives markings thereon which correspond to the characters 14 so that a facsimile of the appearance of the subject tape 12 is produced. The tape 38 is guided by idler rollers 39 and 40 and is propelled through the printing zone by a drive roller 41 and an idler 42. The drive roller 41 is driven by a motor 46 which may be a synchronous motor connected to an alternating current service connection 48. Where the motor 46 and the motor 18 are connected to the same synchronized system, it will not, in general, be necessary to transmit separate synchronizing signals. Synchronizing and phasing signals may be generated and transmitted as described in the United States patent to Artzt, No. 2,326,740, above referred to when this is desirable or necessary.

The recorder or printer unit comprises a magnetic member or core 52 having a central leg 53 and coil supporting legs 56 and 57. The core 52, for convenience, may be mounted on a suitable base or other support 59. An armature 62 of magnetic material is movably mounted in any suitable manner so as to complete the magnetic circuit of the core structure 52 and remain in approximately the central position when the recorder is unexcited. This may be accomplished, for example, by employing a torsional mounting spring 63 which is secured at its ends to brackets 64, one of which appears in Fig. 2 of the drawings. The armature 62 is balanced upon and secured to the spring 63, the parts during construction being so arranged that when the magnet structure is unexcited, each end of the armature may be spaced an equal distance from its operating core leg. The armature 62 thus may have a rocking movement imparted to it which is controlled by the magnetic flux densities in the core legs 56 and 57. A straight edge marking blade 67 is formed integrally with or secured upon the armature 62 so as to cooperate with a helical blade or blades 68 on a rotatable printing drum 69. An inking roller 72 having an ink saturated absorbent periphery 73 bears against the helical blade 68. The rotatable drum 69 and the driving roller 41 may be driven from the motor 46 through a gear device 76 similar in function to the gear device 21 of Fig. 1 of the drawings. It will be understood that carbon transfer record-

ing may be practiced as described hereinafter in connection with Fig. 5 of the drawings.

The magnetic leg 56 of the core 52 is provided with a coil 79, and the leg 57 is provided with a coil 81. In the illustrative example, the coil 79 is arranged so as to be selectively responsive to the lower frequency signals generated upon scanning the subject copy. The coil 81 is arranged to be selectively responsive to the higher frequency signals generated upon scanning the subject copy. Selective response is or may be obtained by choosing different inductance values for each coil or by resonating the coils at the desired response frequency by employing the capacitance values of other elements of the system such as the filters to be described.

A high pass filter 83 has the response characteristic indicated by reference character 85 on Fig. 3. A low pass filter 88 has a response characteristic 89, also shown on Fig. 3. In the illustrative arrangement which is designed for the signal frequencies stated above by way of example, the low pass filter cuts off at 1800 cycles, and the high pass filter cuts off at 900 cycles. Conversely, attenuation for the low pass filter begins at 900 cycles and at 1800 cycles for the high pass filter. A transformer 91 provides a convenient means for transferring signals from the amplifier 34 to the filters 83 and 88. The transformer is provided with a center tapped secondary 92 so that the center tap serves as a common connection for the coils of the recorder structure. The low pass filter 88 is connected with the coil 79 by a connection 94, and the high pass filter 83 is connected to the coil 81 by a connection 96.

In operation of the printer unit disclosed in Fig. 2 of the drawings, the balanced armature 62 takes the place of a discriminator when fed from suitable filters such as the filters 83 and 88. For example, when a dark portion of the subject copy 12 is scanned, the response of the filter 83 is at the level indicated by reference character 99 on Fig. 3, whereas, the response of the filter 88 is indicated at 101. The armature 62, therefore, is actuated to bring the tape 38 backed by the printer blade 67 into contact with the printing helix 68. When the white condition is restored, the coil 79 will be energized to a greater extent than the coil 81, and the armature 62 will be maintained in a position such that the tape does not contact the helix 68. Shading coils in the form of highly conductive rings 103 and 104 act to prevent vibration of the armature 62 at frequencies approaching signal frequencies thereby to avoid recording of a dot pattern.

Even with the carrier signal applied directly to excite the magnetic circuits of the recorder structure without demodulation, it is to be noted that the marking instrumentality comprising the armature 62 and the printer bar 67 has two definite positions in the illustrative example corresponding to the two light reflective conditions of the subject copy 12. This provides clean-cut recordings with good definition from a frequency modulated carrier, heretofore obtainable only by resorting to a demodulating process and push-pull amplification with a special amplifier. While the light reflective properties of the surface of the subject copy have been mentioned, it will be understood that the transmitter pickup may be operated by the light transmitting properties of the subject copy and that image signal reversal may be employed at the transmitting station in either case.

Fig. 5 shows a slight modification of the circuit arrangement of Fig. 3 in which amplification following filter selection is employed. Frequency modulated signals are applied to the primary of a transformer 106, the secondary of which is connected to a low pass filter 108 and a high pass filter 109. The selected frequencies passed by these two filters are amplified in amplifier tubes 111 and 112, respectively, so as selectively to excite printer coils 81a and 79a. These coils are tuned by condensers 114 and 116 whereby the magnetizing current of each coil will be increased at the signal frequency to which it is to respond. Each coil is included in the plate circuit of its corresponding amplifier tube, and one end of each winding is connected to a source of plate voltage 118. The plate current flowing in each coil or the magnetizing effect of the plate current in each coil may be balanced in any desired manner by tube selection, inclusion of ohmic resistance in each tube plate circuit, or by other known methods so that the associated printer armature, for example the armature 62, is balanced.

Fig. 6 shows a recorder constructed in accordance with the invention for page printing. The general arrangement of the recorder may be as shown diagrammatically in the United States Patent No. 2,326,740, to Maurice Artzt, referred to above or in the United States reissue patent No. Re. 20,152, granted to Charles J. Young on October 27, 1936. The recorder comprises a cylinder 121 which is provided with a raised helix 122 and a printer bar 123. In the illustrative example, the recorder is intended to print continuously upon a web or sheet 126 with means (not shown) for interposing carbon paper between the printer bar and the paper web 126, all as disclosed in the Young reissue patent, No. Re. 20,152. Two magnetic units 128 and 129 are shown for moving the printing bar 123 in response to the received image signals. As the units 128 and 129 are or may be similar, a description of one will suffice for both. The printing unit 128, for example, may be provided with an armature 133 which is mechanically balanced about a pivotal support 134. Mechanical balance may be accomplished by tapering the armature or by loading one end. It is also preferred that the magnetic balance of the armature be maintained. The extended portion 136 of the armature is connected in any suitable manner to the printer bar 123. The signal input arrangement is substantially like that shown in Fig. 2 of the drawings and comprises a high pass filter 139 and a low pass filter 141 fed from a transformer 142. Where multiple magnetic units are employed as shown in Fig. 5, it is preferable to include means for balancing the magnetic effect of the signal upon each armature, and this may be accomplished as shown illustratively in Fig. 5 by providing two volume control potentiometers 143 and 144 for the marking coils 145 and 146. Similar volume control potentiometers 148 and 149 are provided for the operating coils on the units. It is believed that in view of the foregoing, the operation of Fig. 5 will be understood without further explanation. At the transmitter a revolving drum type signal pickup arrangement such as is shown in Fig. 1 of Artzt patent, No. 2,326,740, may be employed for scanning pages of copy for transmission.

Having now described the invention, what is claimed and desired to be secured by Letters Patent is the following:

1. A recorder for producing marks in accordance with applied image signals, comprising an

electromagnetic core providing two magnetic circuits, a movable armature associated with said core to complete the magnetic circuits thereof, an exciting coil for each circuit, one of said coils being designed to produce maximum magnetization in one magnetic circuit when excited by image currents of lower frequencies to move the armature in one direction, the other of said coils being designed to produce maximum magnetization in the other magnetic circuit when excited by image currents of a higher frequency to move the armature in another direction, and a marking device associated with said armature.

2. A recording system for producing marks in accordance with image signals represented by frequency variations of a carrier, comprising a filter for separating the higher frequency components of the carrier, a second filter for separating lower frequency components of the carrier, a recorder, control means in said recorder having an operative connection to said high pass filter, additional control means in said recorder having an operative connection to said low pass filter, and a movable recording instrumentality operative to be moved selectively in response to both control means to produce marks on a recording sheet.

3. Apparatus for producing a copy of a picture, drawing, or other subject matter in facsimile on a record surface, comprising a facsimile copying device responsive to an alternating current, the frequency of which varies in accordance with the elemental areas of the subject matter to be recorded, means to cause the copying device to scan the record surface, and means for applying separated components of the frequency modulated current to the copying device, said copying device being responsive once at the time of application of one separated frequency component and being responsive again when the application of the separated component ceases and at the time of application of another separated frequency component.

4. Apparatus for producing a copy of a picture, drawing, or other subject matter in facsimile on a record surface, comprising a facsimile copying device having a plurality of means responsive to an alternating current, the frequency of which varies in accordance with the elemental areas of the subject matter to be recorded, means to cause the copying device to scan the record surface, means for applying separated components of a given frequency of the frequency modulated current to the alternating current responsive means, said copying device moving once at the time of application of a separated frequency component to one of said alternating current responsive means and moving again at the time of application of another separated frequency component to another of said alternating current responsive means.

5. A facsimile recording system for providing marks in accordance with image signals represented by frequency variations of a carrier, comprising a balanced electromagnetic recorder, a pair of operating coils for said recorder, a condenser shunted across each coil to increase the response of the coil to carrier current of a given frequency, a pair of filters, means for applying the signal modulated carrier to said filters, and means operatively connecting each filter to the coil having maximum frequency response at the filtered frequencies.

6. A recorder for recording image signals comprising a balanced electromagnet, balance being obtained by subdividing said electromagnet into

two magnetic paths, an operating coil linked with each path, means to furnish each operating coil with alternating currents of a given frequency, a balanced armature associated with said electromagnet, means to maintain said armature in a balanced unactuated position during absence of current in either coil, and a marking instrumentality carried by said armature for cooperative marking engagement with a record surface upon energization of one of said coils by alternating current of a given frequency said marking instrumentality being maintained out of marking engagement with said record surface upon energization of the other of said coils by alternating current of a different frequency.

7. A facsimile recording system for providing marks in accordance with image signals represented by frequency variations of a carrier, comprising a balanced electromagnetic recorder, a pair of operating coils for said recorder, means associated with each coil to increase the response of the coil to carrier current of a given frequency, a pair of filters, means for applying the signal modulated carrier to said filters, and means operatively connecting each filter to the coil having maximum frequency response at the filtered frequencies.

8. A recorder for providing marks in accordance with marking and spacing signals, comprising a plurality of balanced electromagnetic units, a pair of operating coils for each unit, means to provide marking signals to the marking coils of each recording unit as a group, means to provide spacing signals for the spacing coils of each electromagnetic unit as a group, and volume con-

20 trol means interposed in the connection to one of the group of coils whereby to assist in maintaining balance of the electromagnetic units to marking and spacing signals.

9. A recorder for providing marks in accordance with image signals represented by frequency variations of a carrier, comprising a marking device, a plurality of balanced electromagnetic units operatively connected to said marking device, a pair of operating coils for each unit, means to provide marking signals to the marking coils of each recording unit, means to provide spacing signals for the spacing coils of each electromagnetic unit, and volume control means interposed in the connection to each group of coils whereby to assist in maintaining balance of the electromagnetic units to marking and spacing signals.
